CLAIM

An ornamental design for time board, as shown.

DESCRIPTION

FIG. 1 is a perspective view of the present invention.

FIG. 2 is a front view of the present invention.

FIG. 3 is a rear view of the present invention.

FIG. 4 is a left view of the present invention.

FIG. 5 is a right view of the present invention.

FIG. 6 is a top view of the present invention; and,

FIG. 7 is a bottom view of the present invention.

1 Claim, 5 Drawing Sheets(56)
